T. J. KELLEHER

EYE AND FACE SHIELD FOR EMERY AND GRINDING WHEEL OPERATORS

Witness:

Richard J. Jacka

Inventor:

Thomas J. Kelleher,
By Charles Turner Brown,

Atty.

UNITED STATES PATENT OFFICE.

THOMAS J. KELLEHER, OF CHICAGO, ILLINOIS.

EYE AND FACE SHIELD FOR EMERY AND GRINDING WHEEL OPERATORS.

Application filed December 14, 1923. Serial No. 680,622.

To all whom it may concern:

Be it known that I, THOMAS J. KELLEHER, a citizen of the United States, and a resident of Chicago, in the county of Cook and State 5 of Illinois, have invented certain new and useful Improvements in Eye and Face Shields for Emery and Grinding Wheel Operators, of which the following, when taken in connection with the drawing accompanying 10 and forming a part hereof, is a specification.

This invention relates to a device which is attachable to a horizontal table or to a vertical wall or to a post adjacent to one or 15 more emery or grinding wheels, and adjustable so that a transparent member thereof will be interposed between an emery or grinding wheel and the face of an operator using said wheel for grinding or polishing 20 purposes.

Among the objects of my invention is to obtain a device of the kind recited which is easily mounted on the base of floor grinders of different sizes, and whether the journal 25 bearing of the emery wheel or grinder is secured to said base by one or two bolts on each side thereof; and in case said two bolts are used to secure said journal bearing to said base, said device may be secured in place regardless, within a considerable limit, of the 30 variation in distance between said bolts in the different makes and sizes of floor grinders and emery wheels. An additional object is to obtain a device of the kind recited which 35 is easily mounted in place adjacent to an emery or other abrading wheel, or wheels, upon a wall or post, and which, when mounted, can be readily positioned to suit the needs of the operator, so as to protect his eyes and 40 face from sparks or other material thrown off by the contact of the article which is being ground or polished by its being forced into contact with the revolving emery wheel or other abrading surface; said device being 45 provided with a transparent member which is positioned so as not to interfere with a view of the material being operated on. An additional object is to obtain a device which 50 may be mounted at the rear of the emery or other abrading wheel, and the transparent member thereof may be adjusted to a desired position and angle in front of said emery or other abrading wheel. An additional object is to obtain a device of the kind recited 55 which can be adjusted in a desired position by the operator without recourse to bolts or nuts to maintain the transparent member thereof in said adjusted position. An additional object is to obtain a device of the kind recited which is economically made, durable, 60 and not liable to break or to get out of order. Floor emery wheels or grinders to which this apparatus is specially designed to be attached are made by several manufacturers and in a number of different sizes, in all, 65 however, so far as I am advised, there is a standard having a table or base at the upper end thereof and a journal bearing having a base resting on and secured to said table by bolts. In the smaller sizes of some of said 70 floor emery wheels or grinders there is a bolt in the rear of the base of the journal bearing, extending through said base and into said table, and an additional bolt extending through said base and into said table in front 75 of said standard; while in the larger sizes of said floor emery wheels or grinders, there are a plurality of bolts both in the rear and in front of the standard of the journal bearing extending through the base thereof and 80 into the table of the floor stand. Where a plurality of bolts in front and rear of the standard thereof are used to attach the journal bearing to a table the distance between said bolts varies with the different makes, 85 there being no standard with reference thereto. I have therefore designed a base forming an element of my invention which can be secured to the base of the journal bearing of all makes of floor emery wheels or grinders that I am at present advised of, by simply removing one or two of the bolts attaching the base of the journal bearing to the 90 table of the floor stand, placing said base of my device on the base of the journal bearing and replacing the bolts or bolt previously removed therefrom, or substituting a bolt of the same size but of slightly greater length, in place of said removed bolts; and at the 95 same time I obtain a base which is attachable to a vertical wall or post by one or two bolts, as preferred.

In the drawing referred to—

Fig. 1 is a side elevation of the upper end of a floor stand, a journal bearing secured thereto, an emery or grinding wheel the shaft whereof is rotatably mounted in said journal bearing, and an eye and face shield embodying this invention mounted thereon by a single bolt extending through the base of 105 the device, the base of said journal bearing and into the table of the floor stand.

Fig. 2 is a top plan view of the base of the device attached to the base of the journal illustrated in Fig. 1, by a plurality of bolts, showing a portion of one end of said journal base in top plan view and a portion of a vertical member forming an element of the device in horizontal section.

Fig. 3 is a side elevation of the base of the device, attached to the base of a journal bearing, as in Fig. 2, and showing in vertical section, a portion of said base of the journal bearing, and in side elevation a short section of a vertical member forming an element of the device.

Fig. 4 is a top plan view of the base of the device and of a portion of the base of a journal bearing, and a horizontal section of a vertical member of the device; said parts being assembled in the manner illustrated in Fig. 1.

Fig. 5 is a side elevation of the several parts which are illustrated in Fig. 4, with the base of the device turned 180° from the position thereof which is illustrated in Fig. 1.

Fig. 6 is a side elevation of a section of a wall, or post, and of the base of the device attached thereto by a plurality of bolts; and showing in elevation a street ell attached to said base, and a short section of the lower end of the vertical member of the device secured in one member of said street ell.

And Fig. 7 is a vertical section of the upper end of a modification of the frame of the transparent member of the device, and a side elevation of the member of the device securing the flexible member of the device to said frame, showing in side elevation a short section of said flexible member.

A reference character applied to designate a given part indicates said upper part throughout the several figures of the drawing wherever the same appears.

1, Fig. 1, represents the upper end of the standard of a floor stand. 2 represents a table at the upper end of standard 1. 3 represents the base of a journal bearing, 4 the standard of said journal bearing and 5, 6, bolts extending through said base 3, with the screw threads on said bolt fitting into corresponding screw threads in an aperture in table 2, thereby attaching said journal bearing to said table. 7, 8, respectively represent the members of a two part base forming an element of the invention. 9, 9, represent a reverse bend in members 7 and 8. Where the base members 7, 8, are attached to a table by a single bolt, as 6, Figs. 1, 4 and 5, said members are arranged one over the other, as is well illustrated in Figs. 1 and 5, and the bolt 6 is extended through apertures in both of said members, and into the table 3 and into a screw threaded aperture in table 2. In grouping the members 7 and 8 as above described it is immaterial

whether said members are attached to table or base 3 and table 2 in such manner that the unattached ends thereof are in planes lower than the planes of the attached ends, as is illustrated in Fig. 1, or whether said unattached ends are in planes which are above or higher than the planes of the attached ends, as is illustrated in Fig. 5. Where the two part base formed by members 7 and 8 are attached to base 3 by two bolts, 6, 6, as is illustrated in Figs. 2 and 3, one of the members 7 and 8 is turned, say from the position in which it is illustrated in Fig. 5, so that the side thereof opposite to the side in contact with said table, 3, in said Fig. 5, is in contact with said table, the other of said members (8), being in the same relative position to table 3 as in said Fig. 5; but in contact therewith. 10 represents a vertical standard of the device, and preferably consists of a pipe or tube screw threaded at both ends thereof, as at 11, Fig. 1, the lower one of said ends fitting into corresponding screw threads in an aperture in said members 7 and 8, thereby firmly securing said standard in said base. 12 represents a flexible member well known in the art of electric lighting, and comprising a coil of resilient wire within a coil of wire of tensile material, which is not resilient, 99 said outer coil being made of wire which is substantially triangular in cross section, and wound closely to the coil of resilient wire. The construction of this flexible member forms no part of my invention, and so is not 100 illustrated in detail. 13 represents a head which is firmly secured to one end of the flexible member 12, and is provided with internal screw threads fitting tightly on to screw threads 11 on the upper end of standard 10. 15 represents what is known in the art of piping as a drop elbow, which is provided with lugs or ears 16, 16; said lugs having apertures through which bolts, 17, 17, are extended to secure said drop elbow 110 to any desired base. 18, 18, respectively represent nuts on bolts 17, 17. It will be observed on comparison of Figs. 1 and 7, that the drop elbow 15 is turned in Fig. 7 from the position in which it is illustrated in Fig. 1, so that one of said lugs 16, and bolts 17 are shown in Fig. 1, the other ones thereof are shown in Fig. 7. One end of the flexible member 12 is secured in one (19) end of drop elbow 15, in Fig. 1, and into the other (20) end thereof in Fig. 7. 21, Fig. 1, and 22, Fig. 7, represents a frame and a modification of said frame. Frames 21, 22, enclose a transparent plate 23, the upper end of said frame and plate being illustrated by 125 full lines in Fig. 7; said plate being indicated by broken lines in Fig. 1. Whether the construction of the frame 21, which is illustrated in Fig. 1, is used, or the modified construction illustrated in Fig. 7, the 130

lugs or ears 16, 16, are applied to one side of the frame and secured thereto by bolts 17, 17 and nuts 18, 18, as hereinbefore recited; or by other suitable means, as rivets.

5 Whichever form of frame is adopted, the plate 23, of transparent material is not necessarily changed in size, or shape.

Where it is desired to attach the members 7, 8, of the two part base of my device to a vertical wall or post, said members may well be brought into the same relative position as is illustrated in Figs. 2 and 3, and attached to said wall or post by bolts 6^a, 6^a, as is illustrated in Fig. 6. The slight variation of

15 said members from a vertical plane not affecting the efficiency of said members as a base. 24, Fig. 6, represents a street elbow, which is interposed between the lower end of standard 10, and said members 7, 8, when

20 said members are in substantially vertical planes; one end of said street elbow being screw threaded in the ordinary way, and fitting into corresponding screw threads provided therefor in apertures in said members

25 7 and 8. By interposing the street elbow 24, the standard is mounted and maintained in a substantially vertical position, as in Figs. 1, 3 and 5. It is evident that where the members 7, 8, are attached to a vertical

30 wall or post by a single bolt, said members may be placed in the same relative position as they are illustrated in Fig. 5, and the bolt extended through apertures in said members and into the vertical wall or post in the

35 same manner and direction as bolt 6 in said Fig. 5, extends through apertures therein and into table 3. When so secured to a vertical wall or post both ends of members 7, 8, will be in planes parallel to the plane of

40 the wall or post, and the street elbow 24 will be attached to said members 7, 8, in the same manner as is illustrated in Fig. 6. It will be noted that by my constructing a two part base of members 7, 8, in the manner herein-

45 before described, said base is attachable either to a horizontal table or to a vertical wall or post by one or two bolts and that when two bolts are used the distance from one thereof to the other may vary by a con-

50 siderable amount with a corresponding difference in the angular relation of said members 7, 8.

I find, in practice, that where one end of the flexible member 12 is secured to a vertical member, as standard 10, and said flexible member is bowed or curved so that the other end thereof is in an inclined plane, say substantially as illustrated in Fig. 1, said flexible member will retain said position, the

60 weight of the several parts on the inclined end thereof not being sufficient to change the position of said flexible member 12 throughout the body part thereof, or at said inclined end; and that the frame 21, (or 22),

65 will not be moved from an adjusted posi-

tion, either because of the weight of said frame and transparent member 23 therein, and drop elbow 15, or by reason of the vibration of the emery or grinding wheel 25.

The manner of assembling the several 70 members of the device being simple, and having been hereinbefore recited, no further explanation thereof appears desirable or necessary.

I claim:

1. In an eye and face shield, a two part base, consisting of corresponding members respectively provided with apertures adjacent to the ends thereof, the apertures adjacent to one of the ends in both said members 80 screw threaded and adapted to register, one of said parts adapted to be imposed on the other, and also adapted to be imposed on the other at the end provided with screw threaded apertures and to be in the same 85 plane at the other ends thereof, a vertical standard secured in said screw threaded apertures, and a non-extensible flexible member secured to said standard, in combination with a frame, a transparent member in said 90 frame, and means to attach said frame to the free end of said flexible member.

2. In an eye and face shield, a two part base, consisting of corresponding members respectively provided with apertures adjacent to the ends thereof, the apertures adjacent to one of the ends in both said members 95 screw threaded and adapted to register, one of said parts adapted to be imposed on the other, and also adapted to be imposed on the other at the end provided with screw threaded apertures and to be in the same 100 plane at the other ends thereof, a vertical standard secured in said screw threaded apertures, and a non-extensible flexible member secured to said standard, in combination with a frame, a transparent member in said 105 frame, a drop elbow, said flexible member attached to one element of said elbow, lugs on said elbow and means to attach said lugs 110 to said frame.

3. In an eye and face shield, a two part base, consisting of corresponding members, a standard, means to attach said standard to said base, the members of said base being adapted to permit variation in their angular relation and the free ends of said members provided with apertures, one of said parts adapted to be imposed on the other, and also adapted to be imposed on the other at the end provided with screw threaded apertures and to be in the same plane at the other ends thereof, in combination with a frame, a transparent member in said frame, a non-extensible flexible member, means to attach one end of said flexible member to said standard, and means to attach the opposite end of said flexible member to said 120 frame.

4. In an eye and face shield, a two part

- base comprising corresponding bars, respectively provided with a reverse bend whereby when assembled one end of said bars are in the same horizontal plane 5 and the opposite end of said bars in parallel planes, apertures adjacent to the ends which are in the same horizontal plane and screw threaded apertures adjacent to the opposite ends, adapted to register, 10 a vertical standard the ends thereof provided with external screw threads, and one of said ends fitting into the screw threads in said screw threaded ends, all in combination.
- 15 5. In an eye and face shield, a two part base; a standard, means to attach said standard to said two part base, said means comprising external screw threads on said standard and screw threaded apertures adjacent to one end of said parts adapted to engage 20 said external screw threads, whereby one of said parts is imposed on the other at said ends, to permit the free ends of the members of said base to be moved, and said members provided with apertures adjacent to the free ends thereof, whereby the distance between said apertures is adjustably variable, in combination with a frame, a transparent member in said frame, a flexible member, means to attach one end of said flexible member to said standard, and means to attach the opposite end of said flexible member to said frame.

THOMAS J. KELLEHER.
